[57] ABSTRACT

A safety helmet includes a lower rear semi-spherical section adapted to slide over an upper semi-spherical section in response to a high impact accident causing flexure of the wearer's neck. The first section is pivoted to the second section about an axis which is located as nearly as possible to the normal pivot of the cervical skull axis. Position stops are provided to limit the downward and upward pivotal movement of the lower section. The lower edge of the lower section is broadly flanged and well padded to diversify and cushion impact with the neck of the wearer and is designed to engage the wearer's neck at a point below the fragile upper cervical area and, in particular, below the third vertebra.

FIG. 1

FIG 2

FIG 3

FIG 4

SAFETY HELMET

BACKGROUND OF THE INVENTION

This invention relates to safety helmets and is particularly concerned with safety helmets which are designed to prevent excessive injury to the neck and vertebrae of the wearer.

Safety helmets have come into wide use in response to the danger of serious injury to motorcycle drivers and drivers in automotive races. In the past, such safety helmets have become substantially standardized and consist of substantially semi-spherical shells of a suitable, rigid and durable material, such as a high impact plastic or fiberglass impregnated with resin. The shells are provided with suitable padding about their interiors to engage on and about the head.

While such safety helmets are extremely effective in protecting a wearer's head against injury, they fail to protect the wearer against serious neck injuries and, indeed, due to the structure of such helmets, they materially increase the possibility or likelihood of neck injuries. The relatively narrow lower rear edge of the helmet has a tendency to engage the neck of the wearer in response to accidents which cause the head and neck of the wearer to become suddenly and forcibly hyperextended. At this time, the helmet becomes a lethal piece of equipment, the lower edge impinging on the first cervical vertebra, shoving it anteriorly and thus fracturing the odontoid and proceeding forwardly to transect the spinal cord at the C-1 level. This will leave the individual decerebrate with the final outcome, death, occurring within a few hours. There have been proposals in the prior art which have been concerned with avoiding such injuries. In U.S. Pat. No. 3,591,863, for example, it is proposed to provide an elongate, vertically extending neck pad engagable with the back of the wearer's neck and shaped to conform to the wearer's neck when the wearer's head is tipped and his neck is flexed backwardly a predetermined extent to provide support to the cervical portion of the wearer's spine and occipital portion of the wearer's skull. However, the mounting means for the pad includes an arm depending downwardly and forwardly from the lower rear edge portion of the helmet which normally engages the rear side of the pad and a downwardly depending flexible strap for supporting the pad. Since the arm and strap are engaged with the pad and the pad is engaged with the wearer's neck, there is no delay in the impact time with the result that even a minor impact will cause increased pressure against the wearer's neck. A more severe accident may result in failure of the pad driving the narrow lower edge of the arm or the lower end of the strap, which are relatively close to the wearer's neck to begin with, into the wearer's neck causing injury to the cervical area. Moreover, a helmet of this character is inherently uncomfortable because of the chafing and irritation caused by the pad always in engagement with the back of the wearer's neck.

In U.S. Pat. No. 3,230,544 it is proposed to provide athletic headgear with a hinged rear flap which has the purpose of avoiding the impact of the rear rim of the helmet on the back of the neck. However, this helmet is subject to a number of limitations making it unsuitable for protection against injury in high impact accidents. The rearwardly extending flap will, when extended, offer no side protection for the cut out area

during impact. Moreover, the lower edge of the hinge would provide a critical cutting edge to the wearer's spine. There is no means for stopping the rearward movement of the flap, thus resulting in excessive flexure of the wearer's neck. In addition, the hinged flap is maintained in engagement with the wearer's neck causing chafing and irritation thereto. Also, in a dorsalfowards projected fall, the hinged flap could be projected forwardly and sever the spinal column or even decapitate the wearer.

It has also been proposed in the prior art to provide a protective helmet of the "hard hat" type with pivoted sections. This is shown in U.S. Pat. No. 3,514,787. However, the purpose of the pivoted sections in this patent is to provide a protective hat which can be collapsed to a more portable condition. When the hat is used it is latched in its full open position and thus, the several sections will be maintained in their extended position during the impact of an accident.

SUMMARY OF THE INVENTION

It is accordingly the principal object of the present invention to provide an improved safety helmet which avoids the drawbacks and limitations of the prior art.

More particularly, it is an object of the present invention to provide an improved safety helmet which reduces the possibility of injury to the neck and spine of the wearer during accidents which cause hyperextension of the wearer's neck.

To this end, the invention contemplates the provision of a safety helmet having a pair of semi-spherical sections. A first semi-spherical section is provided to protect the upper portion of the wearer's head, and a second semi-spherical section, which is pivoted to the first section, is intended to protect the lower rear portion of the wearer's head. The second section is slidably engaged with a semi-spherical surface of the first section, and pivots upwardly in response to the forces generated during hyperextension of the wearer's neck during a high impact accident. For this purpose, the pivot axis for the second section is located as nearly as possible to the normal pivot of the cervical skull axis of the wearer. A spring is provided to bias the lower section downwardly to a position protecting the lower rear portion of the wearer's head, and a pair of stops are provided to limit upward and downward movement of the second section. The upward movement is limited so that flexure of the wearer's neck will be less than 50°. The lower edge of the second section is broadly flanged and well padded to broaden and cushion the impact against the wearer's neck. Moreover, the lower edge is so positioned that impact will be well below the fragile upper cervical area and will, in particular, engage the wearer's neck below the third vertebra.

These and other objects, features, and advantages of the present invention will become more readily apparent upon detailed consideration of the following description of a preferred embodiment with reference to the accompanying drawings.

BRIEF DESCRIPTION OF THE DRAWINGS

FIG. 1 is a perspective view of a safety helmet of the present invention;

FIG. 2 is a vertical section view of a helmet of the present invention positioned on the head of a wearer whose skull and spinal column are shown in phantom line;

FIG. 3 is a partial section view taken along the line 3 — 3 of FIG. 2; and

FIG. 4 is a partial section view taken along the line 4 — 4 of FIG. 2.

DETAILED DESCRIPTION OF THE PREFERRED EMBODIMENT

Referring to the drawings, it will be seen that a helmet 10 of the present invention includes a first helmet section 12 to which is pivoted a second helmet section 14. Helmet section 12 is adapted to cover the top and sides of the wearer's head and includes a semi-spherical shell portion 16 made of a durable high impact plastic, such as resin impregnated fiberglass or polycarbonate. Section 12 includes a raised portion 18 facilitating the flow of ventilating air into the helmet as will be presently described. For this purpose, raised portion 18 has a front wall 20 provided with a plurality of openings 22 for admitting ventilating air into the helmet. In order to control the flow of ventilating air, a control valve 24 is provided in the form of a plate having a plurality of corresponding openings which are slidably into alignment with openings 22 to open the openings or out of alignment with openings 22 to close the openings. In order to move slide 24, a handle projects upwardly through a slot 28 provided in the top wall of raised section 18.

The inner surface of helmet section 12 is lined with a padding 30 adapted to fit and protect the wearer's head. This padding is made from a foam plastic material or a foam rubber and serves to cushion impact. Padding 30 includes a plurality of ribs 32 within raised helmet section 18, ribs 32 being separated by grooves 34. This ribbed design secures the helmet on the wearer's head much in the fashion of tire treads securing a car to the road.

An important feature of helmet section 12 is the provision of a shoulder 36 extending upwardly from semi-spherical section 16 at the rear of raised section 18. As will be presently explained, shoulder 36 will serve as an abutment stop to limit upward movement of helmet section 14. In order to limit downward movement of helmet section 14, a second stop is provided in the form of a plurality of spaced, raised protuberances 38 adjacent the rear edge of helmet section 12.

Helmet section 14 is adapted to cover the rear portion of the wearer's head. This section is also formed of a high impact plastic, such as resin impregnated fiberglass or polycarbonate. This section also includes a semi-spherical portion 40. A lip 42 extends downwardly from the upper edge of section 40 and serves to engage with stops 38 when helmet section 14 is in its lowered position and engage against shoulder 36 when helmet section 14 is in its upper position, as will be presently explained.

Helmet section 14 includes a broad lower flange 44 which serves to broaden the impact of the lower edge of the helmet against the neck of the wearer in a high impact accident which causes hyperextension of the wearer's neck. Helmet section 14 is also lined with padding 46 made of the same foam cushioning material as is used to line helmet section 12. It is to be noted that padding 46 includes a lower thickened lip portion 48 beneath broad flange 44, serving to provide greater protection to the wearer's neck upon impact therewith.

Lower helmet section 14 is pivoted on a pair of pivots 50, only one of which is seen in FIGS. 1 and 2, provided on both sides of the helmet. Pivots 50 define an axis

which coincides with a central axis of the semi-spherical surfaces of sections 12 and 14 and is positioned as nearly as possible to the normal pivot of the cervical skull axis of the wearer. This axis extends more or less through the opening of one ear to the opening of the other ear of most individuals.

It will be noted that the semi-spherical shape of helmet portion 40 of section 14 and padding 46 closely conforms to the semi-spherical shape of helmet portion 16. For this reason, lower helmet section 14 is adapted to slide along the outer surface of semi-spherical portion 16 of upper helmet section 12. In order to facilitate this sliding movement, padding 46 is provided with a plurality of grooves 52 which receive the stop projections 38 extending upwardly from the lower edge of upper helmet section 12.

A torsion spring 54 extends around each pivot 50 and includes a first arm 56 engaged against a stop 58 provided on the inner surface of upper helmet section 12 and a second arm 60 having an end engaged against a stop 62 provided on lower helmet section 14. Spring 54 normally biases section 14 to its lower position with lip 42 engaged against stop protuberances 38. When, however, the wearer is involved in an accident causing a whip-lash movement of his head, his head will pivot backwardly to engage the broad flange padding 48 against the back of his neck. This will cause lower helmet section 14 to pivot upwardly against the bias of the spring until lip 42 engages shoulder 36. The position of the shoulder 36 is selected so that the head will flex less than 50°. It has been found that flexure of the neck beyond fifty degrees may cause critical or fatal injury.

The broad lower flange 44 of lower helmet section 14 is so positioned that it will impact against the neck of the wearer at a point well below the fragile upper cervical area in a lower stronger cervical area. In particular, it has been found that danger of serious, and fatal, injuries is greatly reduced if the impact is provided below the third vertebra.

Helmet 10 is provided with a pair of chin straps 64 and 66 which are attached at one end to pivots 50. A buckle fixture 68 is provided at one end of strap 66 so that the chin strap may be securely fastened when the helmet is in place on the wearer's head.

The use of the helmet 10 of the present invention will be best understood with reference to FIG. 2. In this figure helmet 10 is shown positioned on the head of the wearer. The semispherical shape of helmet section 14 corresponds closely to the semi-spherical shape of the wearer's skull 70. In normal use, lower helmet section 14 is biased downwardly to the lower position as shown in FIG. 2 with lip 42 engaged against stop protuberances 38. If, at this time, the wearer is involved in an accident causing hyper-extension of his neck in a whip-lash fashion, his skull 70 will be pivoted backwardly until the broad flange padding 48 engages against his neck. It is an important feature of the present invention, that the position of broad lower flange 44 and padding 48 is such that this engagement occurs below the upper fragile cervical area. In particular, engagement against the first vertebra 72, the second vertebra 74, or the third vertebra 76 is avoided and engagement with the wearer's neck is in the region of the fourth vertebra 78 or lower. As was explained hereinabove, a problem with prior art helmets resided in the fact that the lower, relatively narrow, edge of the helmet would engage against one of the upper vertebra, causing fatal

or serious injury to the wearer. By confining impact to a point below the third vertebra, the present invention serves greatly to reduce serious injuries. Moreover the broad area of impact provided by broad flange portion 44 results in a sharp reduction in the damage of a critical and/or fatal injury.

While a specific embodiment of the invention has been described herein, it is to be understood that modifications, substitutions and equivalents may be used without departing from the scope of the inventive concept.

The invention claimed is:

1. A safety helmet comprising:

a first semi-spherical helmet section adapted to cover the top portion of the wearer's head; a second semi-spherical helmet section adapted to cover the lower back portion of the wearer's head, said first section being nested within said second section with the lower edge of said second section forming the lower rear edge of said helmet and the upper edge of said second section being engaged on the lower portion of said first section, and pivot means for pivotally connecting said second section to said first section about an axis coinciding with a central axis of the first and second sections whereby the second section is slideable over a semi-spherical surface of said first section; means for biasing said second section downwardly to a position covering the lower rear portion of the wearer's head, said second section, in response to a high impact accident causing whip-lash of the wearer's head, pivoting upwardly in sliding engagement with said first section to minimize injury to the neck of the wearer; and stop means interacting between said first and second sections to limit pivotal motion between said sections such that the lower edge of said second section cannot reach the position of the lower edge of said first section, said lower edge of the second section being in the form of an impact-absorbing flange to prevent injury to the wearer.

2. A safety helmet as recited in claim 1, wherein said second section is pivoted to said first section about a pivot axis which is located as near as possible to the cervical skull axis of the wearer.

3. A safety helmet as recited in claim 1, wherein first stop means limits downward movement of said second section relative to said first section and second stop means limits upward movement of said second section relative to said first section.

4. A safety helmet as recited in claim 3, wherein said second stop means is so positioned that said lower edge of the second section is stopped relative to said first section at a predetermined position which corresponds to flexing of the wearer's neck to less than 50°.

5. A safety helmet as recited in claim 1, wherein said broad flange is covered with substantial padding to cushion impact with the wearer's neck.

6. A safety helmet as recited in claim 5, wherein said lower edge is so positioned that it will engage the wearer's neck at a point below the upper fragile cervical area.

7. A safety helmet as recited in claim 6, wherein said point of engagement of said lower edge is below the

third cervical vertebra.

8. A safety helmet as recited in claim 6, wherein said second section is pivoted to said first section about a pivot axis which is located as near as possible to the cervical skull axis of the wearer.

9. A safety helmet as recited in claim 6, wherein first stop means limits downward movement of said second section relative to said first section and second stop means limits upward movement of said second section relative to said first section.

10. A safety helmet as recited in claim 9, wherein said section stop means is so positioned that said lower edge of the second section is stopped relative to said first section at a predetermined position which corresponds to flexing of the wearer's neck to less than 50°.

11. A safety helmet comprising, in combination: a pair of helmet sections disposed in nested relation so as to provide inner and outer helmet sections, said inner section having a top portion and a rear portion in which said rear portion presents an outer part-spherical surface of generally sectorial form, said outer helmet section being of part-spherical, sectorial form; means connecting the inner and outer sections about a pivot axis coinciding with the central axis of said sectorial surface of the inner section and of said sectorial surface of the outer section for allowing said outer section to swing about said pivot axis relative to said inner section;

said rear portion of the inner section having a free marginal edge portion overlapped by said outer section, first stop means extending along said free marginal edge portion and second stop means extending along a path parallel to but spaced from said first stop means;

said outer section having a lower edge portion presenting an impact-absorbing flange and an upper marginal edge portion, and abutment means along said upper marginal edge portion for engaging said first and second stop means to establish respectively a normal and an abnormal position of said outer section with respect to said inner section, said outer section being of a width greater than the spacing between said first and second stop means whereby said impact-absorbing flange is disposed outwardly beyond said free marginal edge portion of the inner section when said abutment means is in engagement with said second stop means; and means normally maintaining said abutment means against said first stop means for resisting movement of said outer section to said abnormal position thereof.

12. A safety helmet as defined in claim 11 wherein said means normally maintaining said abutment means against said first stop means comprises a spring biasing said abutment means against said first stop means whereby said outer section moves against increasing spring reaction force as said abutment means approaches said second stop means.

13. A safety helmet as defined in claim 12 wherein said first stop means is in the form of spaced projections and said outer section includes a padding liner having grooves receiving said projections.
